PACKAGING TRAY

Richard E. Reny, Bronxville, N.Y., assignor to Keyes Fibre Company, Waterville, Maine, a corporation of Maine

Continuation of design application Ser. No. 78,023, Jan. 2, 1964. This application Dec. 30, 1964, Ser. No. 83,546

Term of patent 14 years

(Cl. D58—13)

FIG. 1 is a top plan view of a packaging tray embodying my new design;

FIG. 2 is a side elevational view; and

FIG. 3 is an end elevational view thereof.

This is a continuation of copending application Serial No. D.78,023 filed January 2, 1964, and now abandoned.

I claim:

The ornamental design for a packaging tray, as shown and described.
